UNITED STATES PATENT OFFICE.

LOUIS P. LAWRENCE, OF PASSAIC, NEW JERSEY.

POWER-BRAKE.

SPECIFICATION forming part of Letters Patent No. 417,194, dated December 10, 1889.

Application filed September 2, 1889. Serial No. 322,770. (No model.)

To all whom it may concern:

Be it known that I, LOUIS P. LAWRENCE, of Passaic, in the county of Passaic, in the State of New Jersey, a citizen of the United States, have invented certain new and useful Improvements in Power-Brakes, of which the following is a specification.

This invention relates to improvements in brakes, operated by means of vacuum, compressed air, steam, gas, or any other fluid.

The object of my invention is to provide a brake of this kind, which can be readily applied and which can easily be adjusted to compensate for the wearing off of the tire.

The invention consists in the construction and combination of parts and details, as will be fully described and set forth hereinafter, and finally pointed out in the claims.

In the accompanying drawings, Figure 1 is a vertical transverse sectional view of my improved brake on the line *x x*, Fig. 2. Fig. 2 is a vertical longitudinal sectional view of my improved brake. Fig. 3 is a horizontal sectional view on the line *y y*, Fig. 2. Fig. 4 is a vertical detail sectional view on line *w w*, Fig. 1. Fig. 5 is a transverse sectional view on line *v v*, Fig. 1.

Similar letters of reference indicate corresponding parts.

The cylinder or chamber A is provided with the side flanges A' A², united at the top and bottom of the cylinder by the curved end pieces A³. The flange A' extends beyond the top and bottom of the cylinder or chamber, and also beyond the front of the same, as shown in dotted lines in Fig. 2, and is provided at both ends with apertures for receiving bolts for screwing it to the locomotive-frame.

The cylinder or chamber A is provided with a head B, provided at its center with a projection B', forming a central depression or recess in the inner surface of said head. A diaphragm C, made of rubber, leather, canvas, or any other suitable air-tight material, is clamped along its edges between the edges of the cylinder or chamber A and the head B, and rests on the inner surface of the front of the cylinder or chamber. The piston D rests on the said diaphragm, and is provided at its center with the tubular projection E, extend-

ing in the direction toward the head B, on the center of which projection a stud or knob F is formed, around which one end of a helical spring F' is placed, the opposite end of the helical spring, which has greater diameter, resting in the pocket or recess formed in the inner surface of the cylinder-head by the projection B', said spring bearing against the piston and pressing the same against the diaphragm C.

The piston D is provided on its front side with two tubular projections H, each having a longitudinal slot H', extending from the piston to within a short distance from the outer end of the projections, said projections passing through suitable apertures provided for the same in the diaphragm. These projections H also pass into elliptical or like pockets J, formed on the front of the cylinder or chamber A, the side walls of which pockets are connected by ribs or wings J' with the walls of the cylindrical compartment K, formed on front of the cylinder and connected by ribs K' with the side flanges A' and A².

In the compartment K a hub L is placed, which has a screw-threaded bore and two opposite external lugs M, which pass into notches N' in the shorter ends of levers N, pivoted by bolts O between the ribs J', the opposite ends of said levers N projecting into the slots H' of the projections H and resting on the inner surface of the outer end parts of the projections. The bolts O pass through the outer flange A² of the cylinder or chamber A and through the ribs J', as shown in Fig. 1.

Into the screw-threaded bore of the hub L a screw-threaded block P is screwed, which is provided with a polygonal aperture for receiving one end of the polygonal push-pin Q, the opposite end of which rests in a recess or groove in the back of the brake-shoe R.

A packing-ring S, made of rubber or other suitable material, is countersunk in a groove in the opening of the block P, and surrounds the push-pin Q and prevents undue rattling.

The brake-shoe R is suspended from a curved link T, pivoted to the shoe and mounted to swing on a bolt U, passed through the flange A² and ribs A⁴ of the chamber or cylinder A, said bolt being provided near its

outer end with an annular groove a , for receiving the upper end of the spring-pressed latch-lever b , mounted to swing on one of the pins O . The upper part of the back of the 5 brake-shoe rests against an adjusting-screw W , screwed into the link T at the bend, by means of which screw the shoe can be adjusted to hang in the proper position in relation to the rim of the wheel.

10 The cylinder or chamber A is provided at the top and bottom with a neck d , to which the pipe for exhausting the air can be coupled, this pipe being connected with the upper neck, the lower end being closed.

15 Two necks are provided to permit of using the device on either side of the wheels.

m is an aperture in the front of the cylinder for the passage of the air.

20 The cylinder or chamber A and the piston therein are curved and made concentric with the wheel-tire. This greatly facilitates fastening and securing the said cylinder or chamber on the frame of the locomotive.

25 By slightly altering the construction and arrangement of parts the brake can be operated by compressed air as well as by vacuum.

The operation is as follows: Ordinarily the piston D rests against the diaphragm, as shown in Fig. 2. When the air is exhausted from 30 that part of the chamber A between the piston and head B , the exterior air acting on the piston presses the same in the direction of the arrow x' , Fig. 2, and thereby the projections H are moved in the same direction and 35 pull those ends of the levers N within them also in the direction of the arrow x' . Thereby the shorter ends of the levers N are moved in the inverse direction, and as they engage the hub they move said hub, the block P , and 40 the push-pin Q in the inverse direction of the arrow x' and press the shoe R against the rim of the wheel, and at the same time the spring F' is compressed. When the vacuum is destroyed—that is, when the brakes are to 45 be released—the weight of the brake-shoe presses the push-pin Q , block P , and hub L in the direction of the arrow x' , and thereby the piston D is moved in the inverse direction of the arrow x' . The spring F' assists in pressing the piston against the diaphragm. The levers N multiply the power produced by exhausting the air from the space 55 between the piston D and head B , and thus with a comparatively small piston area very great power can be obtained. When it is desired to remove the link d , from which the brake-shoe is suspended, it is only necessary to press the lower end of the latch b against its spring, so as to disengage its top end from 60 the bolt U , thus permitting of withdrawing said bolt. As the shoe wears off, the block P must be moved outward according to the wear of the shoe. This is easily accomplished by turning the push-pin Q by means of a suitable key or other implement, whereby the block P is also turned and screwed into or out of the hub, as the said push-bar and the

aperture in the block P for receiving it are made polygonal.

Having thus described my invention, I claim as new and desire to secure by Letters Patent—

1. The combination, with a cylinder or chamber and a piston in the same, of levers pivoted within said cylinder or chamber and acted upon by the piston in said cylinder or 75 chamber, substantially as set forth.

2. In a power-brake, the combination, with a cylinder or chamber and a piston in the same, of a brake-shoe push-bar and pivoted levers for transmitting the motion and power 80 from the piston to the brake-shoe push-bar, substantially as set forth.

3. In a power-brake, the combination, with a cylinder or chamber and a piston in the same, of levers pivoted in said cylinder or 85 chamber and acted upon by the piston and a bar acted upon by said levers, substantially as set forth.

4. In a power-brake, the combination, with a cylinder or chamber and a piston in the 90 same, of lugs projecting from the piston, levers pivoted on the cylinder or chamber, which levers project into said lugs, a hub actuated by said levers, and a push-bar actuated by said hub, substantially as set forth. 95

5. In a power-brake, the combination, with a cylinder or chamber and a piston in the same, of levers pivoted on said cylinder or chamber and acted upon by the piston, a hub 100 actuated upon by said levers, a block mounted adjustably in the hub, and a push-bar in said block, substantially as set forth.

6. In a power-brake, the combination, with a cylinder or chamber and a piston in the same, of levers pivoted on said chamber or 105 cylinder and an adjustable push-bar actuated by said levers, substantially as set forth.

7. In a power-brake, the combination, with a cylinder or chamber, of a piston in the same, levers pivoted on the cylinder or chamber and actuated by the piston, a hub actuated by said levers, a block screwed into said hub and having a polygonal aperture and a polygonal push-bar in said block, substantially as set forth. 110

8. In a power-brake, the combination, with a chamber or cylinder and a piston in the same, of a hub, mechanism for actuating said hub from the piston, a block screwed into said hub and having a polygonal aperture, 115 and a polygonal push-bar in said aperture, substantially as set forth.

9. In a power-brake, the combination, with a cylinder or chamber and a piston in the same, of a hub and mechanism for moving it 120 from the piston, a block in said hub provided with a polygonal aperture, a packing-ring in said aperture, and a polygonal push-bar passed through said packing-ring and into the aperture in the block, substantially as set 125 forth.

10. In a power-brake, the combination, with a cylinder or chamber, of a piston in the same, of slotted lugs projecting from said pis- 130

ton, levers pivoted on the cylinder or chamber and having their ends passed into the slots in said lugs, said levers having notches in their opposite ends and a hub having opposite lugs that pass into notches in the ends of the levers, a block screwed into said hub, and a push-bar in said block, substantially as set forth.

11. In a power-brake, the combination, with a cylinder or chamber and a piston in the same, of mechanism for operating a brake-shoe from said piston, a link for supporting the brake-shoe, and of an adjusting-screw screwed into said link and resting against the back of the shoe, substantially as set forth.

12. In a power-brake, the combination, with a cylinder or chamber, of a diaphragm having two apertures, a piston resting against said

diaphragm and having two slotted lugs passed through the apertures in the diaphragm, pivoted levers having ends in the slots of the lugs, a hub engaged by the opposite ends of said levers, and a push-bar in said hub, substantially as set forth.

13. In a power-brake, a cylinder or chamber made in segmental shape and curved on the same center as the wheel-tire, substantially as set forth.

In testimony that I claim the foregoing as my invention I have signed my name in presence of two subscribing witnesses.

LOUIS P. LAWRENCE.
